BATTERY CHANGER FOR ELECTRIC FORK TRUCKS

Paul J. Doelling, 10105 Cambridge,
Kansas City, Mo. 64134

Filed June 24, 1974, Ser. No. 482,485

Term of patent 14 years

Int. Cl. D12—05

U.S. Cl. D55—1 C

Fig. 1.

Fig. 2.

Fig. 3.

Fig. 4.

FIG. 1 is a perspective view of a battery changer for electric fork trucks showing my new design;

FIG. 2 is a front elevational view thereof;

FIG. 3 is an end elevational view thereof; and

FIG. 4 is a top plan view thereof.

I claim:

The ornamental design for a battery changer for electric fork trucks, as shown and described.
